UNITED STATES PATENT OFFICE.

OWEN L. LEWIS, OF ALLIANCE, OHIO, ASSIGNOR, BY MESNE ASSIGNMENTS, TO THE ALLIANCE TOY & SPECIALTY COMPANY, OF ALLIANCE, OHIO, A CORPORATION OF OHIO.

COASTER-WAGON BODY.

Application filed July 24, 1925. Serial No. 45,810.

The present invention relates to a body construction for toy coaster wagons and provides a body the bottom of which is adapted to be permanently secured to the running gear while the superstructure, consisting of the side and end pieces, is adapted to be readily attached to or detached from the bottom as a unit.

In the accompanying drawings:

10 Figure 1 is a plan view of a body construction embodying a preferred form of my invention;

15 Figure 2 is a side elevation of the body, this view also showing the running gear broken away;

Figure 3 is a side elevation of one of the side pieces of the body; and

20 Figures 4 and 5 are transverse sectional views, illustrating the manner in which the superstructure is attached to and detached from the bottom of the body.

25 Toy wagons as at present constructed have the body built up as a unit and secured to the running gear. Children often like to use these wagons for coasting merely with the flat bottom attached to the running gear. The present invention enables the superstructure of the body to be readily removed when it is desired to use the wagon for coasting and to be replaced when it is desired to use the wagon for other purposes.

30 In the construction illustrated the body comprises the bottom 2 which may consist of one or several pieces secured to the front and rear bolsters 3 and 4 and to the braces 5 and 6. The superstructure of the body comprises the side pieces 7 and 8 and the end pieces 9 and 10. The side pieces 7 and 8 have grooves 11 and 12 extending from their upper edges and terminating adjacent their lower edges. In these grooves fit the end edges of the end pieces 9 and 10. The side and end pieces may be permanently secured together in any suitable manner to form a 35 unitary superstructure.

40 When the superstructure is applied to the bottom the side pieces extend a slight distance below the longitudinal edges of the bottom, while the end pieces have their lower edges notched as at 13 to engage the end edges of the bottom of the body. Secured to the inner face of the side piece 8 adjacent its lower edge and centrally thereof is a small angle 14 which is adapted to

engage the lower face of the bottom of the 55 wagon body, as illustrated more clearly in Figures 4 and 5. The other side piece 7 has an inclined groove 15 in its inner face, the said groove being located adjacent the lower edge of the side piece and centrally thereof. 60 Pivotedly mounted on the lower face of the bottom 2 is a lever 16 which is adapted to have its end swung into the groove 15 when the parts are in the position illustrated in Figure 5. This lever has a wedging action 65 on the walls of the groove, which wedging action serves to securely fasten the superstructure to the bottom of the body.

70 It will be apparent that the superstructure of the wagon body is attached to and removed from the bottom thereof on the same plan as opening and closing a door; that is, the superstructure has a hinging action about the angle 14 on the one side, the other side sliding down over the bottom and being 75 secured by the swinging lever 16. This construction makes it very easy to attach or detach the superstructure without disturbing any of the main parts of the running gear of the wagon.

80 While I have shown and described a preferred embodiment of my invention, it will be understood that the invention is not limited to the details of construction shown, but that it may be otherwise embodied within 85 the scope of the appended claim without departing from the spirit of the invention.

I claim:

85 In a vehicle structure, a bottom, a superstructure having oppositely disposed edges 90 extending below the undersurface of the bottom and oppositely disposed edges engaging the upper surfaces of the bottom for supporting the superstructure, a securing device carried by one of the downwardly extending edges and engaging the undersurface of the bottom and another securing device detachably cooperating with the bottom and another edge, whereby the superstructure is removable from the bottom only by 100 a turning movement about an axis substantially parallel to the plane of the bottom to permit the separating of the first named securing device and the bottom.

105 In testimony whereof I have hereunto set my hand.

OWEN L. LEWIS.
